UNITED STATES PATENT OFFICE.

WILLIAM L. BLISS, OF NIAGARA FALLS, NEW YORK, ASSIGNOR, BY MESNE ASSIGNMENTS, TO U. S. LIGHT AND HEAT CORPORATION, OF NIAGARA FALLS, NEW YORK, A CORPORATION OF NEW YORK.

GENERATOR SUSPENSION.

1,188,399.

Specification of Letters Patent. Patented June 27, 1916.

Application filed November 18, 1912, Serial No. 731,995. Renewed January 4, 1916. Serial No. 70,310.

To all whom it may concern:

Be it known that I, WILLIAM L. BLISS, a citizen of the United States, residing at Niagara Falls, in the county of Niagara and 5 State of New York, have invented new and useful Improvements in Generator Suspensions, of which the following is a full, clear, concise, and exact description, reference being had to the accompanying drawing, 10 forming a part of this specification.

My invention relates to generator suspensions.

It has among its objects to provide compact and improved means for positioning a 15 car lighting generator whereby the proper tension upon the generator belt is maintained and the parts of the generator and suspension are made readily accessible.

Other objects and advantages of my in- 20 vention will hereinafter appear.

In order that my invention may be clearly and fully disclosed, I have illustrated two 25 embodiments of the same in the accompanying drawings.

Figure 1 shows a side elevation of the generator suspension. Fig. 2 shows an end view of the tension member. Fig. 3 shows a side elevation of a modified construction 30 of tension member. Fig. 4 shows a sectional view on line 4-4 of Fig. 3.

The improvements illustrated have a generator-carrying frame composed of two pairs of parallel links 1 and 2 connected by transversely extending cross bars. This 35 frame is pivotally suspended at 3 and 4 from projections or stirrups 5 and 6, rigidly supported on parallel suspension bars 7, which are adjustable with relation thereto as by means of adjustable members 8. The 40 generator 9 is removably attached to the cross bars.

In my improvement, a bell crank lever 10 is pivoted at 11 to the end of the depending portion of the bar 7. This bell 45 crank lever is pivotally connected at one end to a rigid horizontally disposed link 12 adjustably attached to the link 2, as by means of a bolt 13. As illustrated, the bolt 13 clamps the link 12 rigidly to the link 2 50 through an adjustable holding member or

clamp 14 extending around the link. The opposite end of the bell crank lever 10 extends at an angle of substantially 30 degrees to the body portion and is provided with a central bore through which extends the 55 diagonally disposed tension rod 15 or spring carrier. This tension rod is pivoted at its inner end to the suspension on the pivot 4, that is, the same pivot upon which the link 2 is pivoted. The outer end of this rod 60 15 is surrounded by a coiled tension spring 16 which extends between the upper end of the bell crank lever and an adjustable weighted tension nut 17 carried on the threaded outer extremity 18 of the rod. 65 The tension of the spring is thus exerted between the lever attached to the suspended frame and the stirrup or projection 6 rigidly carried by the suspension member 7.

When the generator tends to swing to- 70 ward the left, that is, toward the pulley on the driving axle, the bell crank lever 10 is turned about its pivot 11 to compress the spring 16. The effect of this is to store energy in the spring 16 which opposes the 75 continued movement of the generator, and tends to return the generator to its normal position, wherein the links 1 and 2 are vertical. Likewise, when the suspension is swung to the right, the pressure upon the 80 spring is reduced, allowing the spring to expand and act as a cushioning means preventing the overswing of the generator when it tends to return. Thus the bell crank lever tends to coöperate with the 85 spring to maintain the generator within the desired limits of movement in which the proper tension upon the belt is maintained.

In Figs. 3 and 4 I have illustrated a modified form of construction wherein the ten- 90 sion rod 15, instead of extending diagonally, as in the construction heretofore described, is vertically disposed in a plane parallel to the plane of the generator supporting links. In this construction, the bell crank lever 10 95 is provided with a lug extending substantially at right angles thereto, instead of substantially at an angle of 30 degrees, as in the case of the construction heretofore described. Further, in this case the tension 100

rod is adjustably attached to the threaded end of the adjustable member 8 by means of nuts 20. As illustrated, the upper end of the tension member may be provided with 5 an eye adapted to be received between the nuts 20 and encircle an inner bearing member 21. Obviously, in this form of construction, the operation of the tensioning means is substantially the same as that heretofore 10 described.

By reason of my improvement I am able to eliminate the necessity for twisting the downwardly extending end of the heavy suspension bar 7. I am further able to 15 arrange the tension means more compactly so that the generator is more readily accessible from the side of the truck. Further, the parts are so arranged that there is a minimum of wear upon the same and may 20 be of such a rugged construction as to withstand long use in service. At the same time, the device is exceedingly simple in construction and may be very readily and cheaply manufactured.

25 While I have herein specifically described two embodiments of my invention, it is to be understood that the forms shown are susceptible of modification and that the improvements whereby ruggedness of construction and accessibility of parts are obtained may be employed on other types of suspension than the specific embodiments herein illustrated.

What I claim as new and desire to secure 35 by Letters Patent of the United States is:—

1. A generator suspension comprising suspension bars, a swinging frame depending therefrom, and a spring-pressed lever for positioning said frame pivoted to a depending 40 portion of one of said bars.

2. A generator suspension comprising suspension bars having depending portions at their ends, a swinging frame pivoted to said bars adjacent their depending portions, and 45 a spring-pressed lever pivoted to the end of the depending portion of one of said bars, one end of said lever being pivotally attached to said swinging frame.

3. A generator suspension comprising a 50 pair of parallel suspension bars having depending ends, a swinging generator supporting frame pivoted to said bars adjacent said ends, a lever pivoted to the depending end of one of said bars and pivotally connected at one end to said swinging frame, a tension rod extending through the other end of said lever and attached to said suspension at a point above the lever, and a tension spring normally bearing against one 55 end of said lever.

4. A generator suspension comprising a 60 pair of parallel suspension bars having depending ends, a swinging link pivoted to said suspension bars and depending therefrom, a lever pivoted to the depending end

of one of said bars, means pivoted to the lower end of said lever connecting the same to the lower end of said link, a diagonally disposed tension rod pivoted upon the same pivot as said swinging link and extending 70 through the upper end of said lever, and means normally holding the lower end of said lever in parallel relation with said swinging link.

5. A generator suspension comprising suspension bars having depending ends, a pair of parallel links pivotally supported by said bars adjacent said depending ends and forming a single swinging frame, a bell crank lever pivoted upon the depending end of 75 one of said bars, means connecting one end of said bell crank lever to one of said links, a tension rod pivoted to the pivot of one of 80 said links and extending through the other end of said bell crank lever, and a tension 85 spring carried by said rod and normally bearing against the end of said bell crank lever.

6. In combination, a pair of parallel suspension bars having depending portions 90 extending substantially at right angles thereto, a pair of depending links extending at right angles thereto, and pivotally mounted thereon, a generator supported by said links, a horizontally disposed member 95 for adjusting said links connected to the same at the pivot points thereof, bell crank levers pivoted to the depending ends of said suspension bars, said bell crank levers having their lower ends in parallel relation to 100 said links, means movable with said generator and pivotally connected to said bell crank levers for imparting thereto the swinging movement of said generator, tension rods pivoted to said links and adjustable therewith, said tension rods extending diagonally with respect to the links through the upper ends of said bell crank levers, and tension springs carried upon the outer ends 105 of said rods and normally holding the lower 110 ends of said bell crank levers in vertical position.

7. Means for supporting a generator on a car, said means including suspension means rigidly attached to a portion of the car, a 115 projection rigidly attached to said suspension means, a generator carrying member pivotally suspended from said suspension means, a lever arm attached to said suspended member, and a tension spring exerting 120 its force between the projection on the suspension member and the lever arm to maintain said suspended member in position.

8. Supporting means for a car lighting generator, said means including suspension 125 means rigidly attached to a portion of the car, a swinging generator-carrying frame pivotally suspended from said suspension means, a bracket rigidly attached to said suspension means, a lever arm attached to 130

said frame, a spring carrier attached to one end of said bracket, and a tension spring surrounding said carrier and exerting its force between said bracket and said lever 5 arm to maintain said suspended frame in position.

In witness whereof, I have hereunto sub-

scribed my name in the presence of two witnesses.

WILLIAM L. BLISS.
